UNITED STATES PATENT OFFICE.

FRED B. HAYES, OF FORT WAYNE, INDIANA.

ATTACHMENT FOR METERS.

1,146,704.

Specification of Letters Patent.

Patented July 13, 1915.

Application filed November 30, 1914. Serial No. 874,807.

To all whom it may concern:

Be it known that I, FRED B. HAYES, a citizen of the United States, residing at Fort Wayne, in the county of Allen and State of Indiana, have invented certain new and useful Improvements in Attachments for Meters; and I do hereby declare the following to be a full, clear, and exact description of the invention, such as will enable others 10 skilled in the art to which it appertains to make and use the same.

This invention relates to new and useful improvements in attachments for meters and has for its principal object to provide 15 a device by which an exact reading may be secured.

Another object of the invention is to provide a device wherein the authorized person inserts a bill or card and causes the 20 reading of the meter to be perforated therein, thereby insuring an accurate record.

Another object of the invention is to provide a means for locking the device in inoperative position when it is not in use.

25 A further object of the invention is to provide a device which when it is in operative position allows the figures and pointer to be easily seen.

A still further object of the invention is to 30 provide a frame carrying a relatively soft pad, which presses the card against the perforating means when it is desired that the impression be made.

A more specific object of the invention is 35 to provide a means for pressing the pad against the teeth under a relatively heavy pressure to insure the proper perforation of the bill or card.

With these and other objects in view, the 40 invention consists in the novel combination and arrangement of parts which will be fully set forth in the following specification and accompanying drawings, in which,

Figure 1 is a fragmentary view of a meter 45 showing the attachment as it would appear when applied thereto from a side. Fig. 2 is a vertical sectional view taken on line 2—2 of Fig. 1. Fig. 3 is a horizontal sectional view taken on line 3—3 of Fig. 1.

50 Fig. 4 is a vertical sectional view taken on line 4—4 of Fig. 1 and showing the device in position to be operated. Fig. 5 is a vertical sectional view taken on line 5—5 of Fig. 4. Fig. 6 is a vertical sectional view 55 taken on line 6—6 of Fig. 2. Fig. 7 is a view similar to Fig. 6 showing the device in

its operative position and as it would appear when making the impression. Fig. 8 is a horizontal sectional view showing the arrangement of valves and gearing. Fig. 9 60 is a perspective view of the frame carrying the impression pad, and Fig. 10 is a detail perspective view showing the means for forcing the impression pad against the needles.

65 Referring now to the drawings by characters of reference, the numeral 1 designates the meter which is provided with the usual gear train designated generally by the numeral 2 which gear train is arranged to rotate the pointers 3 which pointers are provided with suitable needle points 4 which are designed to indicate by pointing toward the letters 5, which are also formed of needle points, and thereby indicate the amount 70 of gas or electricity which has been used. The casing in which the impression device will be more fully hereinafter described is mounted and designated generally by the numeral 6 and comprises a top and bottom 75 wall 7, the rear wall 8 which also forms a portion of the front wall of the meter 1. This rear wall 8 is preferably of greater thickness than the walls 7 to form a bearing for the shafts on which the pointers 3 are 80 mounted.

85 The front wall 9 of the casing 6 is provided with a suitable rectangular side opening 10 which is provided with a transparent closure 11 as clearly shown in Fig. 5. A 90 suitable thickened portion 12 is formed at the upper rear corner of each end wall of the casing and this portion is provided with a ground tapered aperture in which the hollow shafts or turning plugs which will 95 be hereinafter more fully described fits. The turning plug or hollow shaft above referred to is best illustrated in Fig. 10 and comprises a hollow cylindrical body 11 which is slightly tapered throughout its entire length and provided at its reduced end with suitable screw threads 12 with which 100 the nuts 13 coöperate in holding the same in close contact with the walls of the apertures in which the device is journaled. This 105 cylindrical body is provided with the diametrically opposed longitudinal slots 13, the use of which will appear as the description proceeds. Formed integrally near each end of the cylindrical body 11 are the arms 14 110 which extend in a plane parallel to the axis of the slots and these arms are provided

with suitable rollers 15, the use of which will appear hereinafter.

Secured to the end of the cylindrical body 11 opposite the screw threaded portion 12 5 is a lever 16 which is designed to remain on the exterior of the casing 6 and is provided with the enlargement 17 which forms a thumb piece for an obvious purpose. A suitable upstanding portion 18 is formed 10 intermediate the ends of the lever and is provided with the longitudinal slot 19 which is designed to receive the locking bolt which will be more fully hereinafter described.

15 A suitable transversely extending slot 20 is formed near each end of the body 11 and these slots are spaced slightly inwardly from the arms 14 and are designed to receive the arms of the inner cylindrical body which 20 will be described in the following paragraph.

The inner cylindrical body or turning plug hereinbefore mentioned, is designated by the numeral 21 and tapers throughout 25 its entire length and this body is provided at its reduced end with the threaded portion 22 which is designed to receive the nut 23 to hold the device in operative position in the tapered bore formed in the cylindrical 30 body 11. A suitable lever 24 is formed on the body 21 at the end opposite the threaded portion 22 and this lever terminates in the thumb piece 25 by which the same is operated. The upward extension 26 having the longitudinal slot 27 formed therein 35 is formed on the upper edge of the lever 24 and this slot and extension are arranged to aline with the extension 18 and slot 19 to receive the locking bolt which will be more 40 fully hereinafter described. A suitable longitudinal slot 28 is formed intermediate the ends of the cylindrical body 21 and is arranged to aline with the slot 13 formed in the cylindrical body or turning plug 11 45 hereinbefore referred to. Extending angularly and in a plane parallel to the axis of the slot 28 is a rectangular frame designated generally by the numeral 29 which comprises the inner bar 30 and the outer bar 31 50 which inner and outer bars are connected by the side bars 32. Suitable ears 33 are formed with the outer bar 31 joins the side bars 32 and these ears are provided with the apertures 34, the use of which will appear 55 hereinafter. Suitable offset portions 35 are formed at the points where the bars 30 joins the bars 32 and these offset portions are provided with the apertures 36 and are extended as at 37 and secured to the body 60 21 to form a rigid connection between the body and the frame. Extended through the apertures 34 and 36 are the rivets or bolts 38 which are provided with the heads 40 and these bolts extend through the ears 39 65 formed on the pressure pad designated gen-

erally by the numeral 41. This pressure pad comprises a body 42 being formed with the peripheral flange 43 on which the ears 39 are formed. This flange 43 extends upwardly from the side of the body 42 to form a shallow pan in which suitable soft felt or similar material 44 is held.

70 The frame 29 is formed with the stops 45 which are designed to engage suitable lugs 46 which are formed on the end walls of the casing 6. These stops are to limit the downward movement of the frame 29 and hold the same in spaced relation to the wall 8 when the device is in operative position. Suitable coil springs 47 surround the bolts 80 or rivets 38 hereinbefore referred to and are to exert pressure on the face of the ears 39 to normally force the body 42 into place in the frame 29. Extending laterally from the end walls of the body 42 are the sockets 48 85 which are designed to receive the rollers 15 carried by the arms 14 and form a bearing therefor, so that when pressure bears on the arm, the body will remain substantially vertical.

90 In order that the device may be locked in inoperative position, there is provided the guide 49 in which the locking bolt 50 is 95 slidable, which guide is provided with the upstanding ear 51 having formed therein the central aperture 52 which meshes with the aperture 53 formed in the ear 54 carried by the locking bolt. The forward end of this locking bolt is adjacently extended as at 55 and is passed through the slots 19 and 27 100 formed in the upstanding portions 18 and 26, respectively, which are in turn respectively formed on the levers 16 and 44. When the device is locked, the bolt is turned through the alining slots and a suitable padlock 56 is arranged so that its shackle 57 105 passes through the apertures 51 and 53 and thereby prevents the bolt from being withdrawn when the lock is unlocked.

110 It will be apparent from the foregoing when it is desired to take the meter reading, the authorized person unlocks the padlock and slides the bolt 50 into unlocked position whereupon he swings the arm 24 downwardly until the same stops whereupon the 115 stop 45 abuts the stops 46 and hold the frame in operative position. The card or bill is then inserted through the alining slots 28 and 13 so that it passes in the card receptacle 58 which is secured to the body 42 120 and is provided with the flared mouth 59 which acts as a guide. After the card has been forced inwardly as far as possible, the lever 16 is then pressed which will cause the body 11 to rotate and thereby swing the 125 arms 14, thus forcing the body 42 and card holder 58 toward the needle points so that the needle points will penetrate the card or bill and partially enter the soft material 44 which forms the back support therefor. The 130

movement of the second lever is against the pressure of the springs 47 and as soon as the operator removes his thumb from the thumb piece 17 of the lever 16 it will be apparent 5 that the said lever will spring outwardly into the position shown in Fig. 5 thereby removing the card from the needle points and placing the same in such a position as to permit to be removed. The bill or card is 10 then removed and it will be clearly seen that an accurate record is made which will remove any apprehension on the part of the consumer that the meter is not read correctly and thereby insure the public of strict 15 honesty when dealing with public service corporations. It is also apparent that with the use of such a device, the public service corporations will not be troubled with complaints from dissatisfied consumers, as a 20 positive record may always be obtained and there is obviously no danger of misreading the meter.

While in the foregoing there has been shown and described the preferred embodiment 25 of this invention, it is to be understood that such changes may be made in the combination and arrangement of parts as will fall within the spirit and scope of the invention as defined in the appended claims.

30 What is claimed is:—

1. In combination, a meter, needles forming the characters and pointers of the meter, a casing secured to the meter, a pair of turning plugs journaled in the casing, one 35 of said plugs being within the other, and both of said plugs being slotted to receive a bill, means carried by the plugs to force the bill against the needles to take an impression of the reading of the meter, and means to 40 rotate the plugs to their operative and inoperative positions.

2. In combination, a meter, needles forming the characters and pointers of the meter, a casing secured to the meter, a turning plug 45 journaled in said casing, said plug tapering throughout its entire length, and being provided with a tapered aperture throughout its entire length, means to cause the tapered plug to bind against the walls of the aperture through which it extends in the casing, a second tapered plug rotatable within the 50 first mentioned plug, both plugs being provided with alining slots and both plugs

being designed to form fluid tight joints to prevent any leakage when in their closed 55 position, means carried by the turning plug to force a bill against the needles and thereby take an impression of the reading of the meter, and means on the interior of the casting to operate the device. 60

3. In combination, a meter, needles forming the characters and pointers of said meter, a casing secured to the meter, turning plugs in the casing, said turning plugs extending beyond one end of the casing, levers secured 65 to the extensions of the turning plugs, a frame carried by one of the turning plugs, a pad carried by the other turning plug, spring means holding the frame and pad normally against each other, and means to 70 force the pad inwardly against the needles.

4. In combination, a meter, needles forming the characters and pointer for said meter, a casing secured to the meter, said casing being provided with a pair of opposite apertures, one of which is of less diameter than the other, a tapered plug within the apertures and arranged to rotate therein, said plug being provided with tapered bore throughout its entire length, a second plug 80 extending into the tapered plug, the second plug being tapered, means to hold the plugs in their respective aperture, levers on the enlarged ends of the plugs, said levers being disposed externally of the casing, means to 85 cause the plugs to form a fluid tight joint within the casing, a frame carried by the first mentioned plug, a stop on the frame arranged to project laterally therefrom, a stop within the casing and arranged to engage 90 the first mentioned stop to hold the frame vertical, rivets extending through the frame, a pad, a rivet extending through the pad, springs interposed between the ends of the rivets and the pad to hold the same against 95 the frame, and means carried by the internal plug to force the pad inwardly and against the needles to cause the same to make an impression on a bill when the meter is being read. 100

In testimony whereof I affix my signature in presence of two witnesses.

FRED B. HAYES.
